poration of New York

Application June 27, 1936, Serial No. 63,529

Term of patent 3½ years

To all whom it may concern:

Be it known that I, Charles R. Kovar, a citizen of the United States, residing at 102-32 Park Lane South, Richmond Hill, Long Island, in the city of New York, county of Queens, and State of New York, have invented a new, original, and ornamental Design for a Glove, of which the following is a specification, reference being had to the accompanying drawing, forming part thereof.

Figures 1 and 2 are respectively a front view and a back view of a glove embodying my new design.

The entire glove is of ribbed fabric, the texture of which is shown in the drawing. The ribs are arranged circumferentially except in the trimming of the cuff portion. The cuff portion is sharply indented toward the wrist along the inner and outer edges of the glove as shown in Figure 2, and the material of the glove is gathered at the wrist.

I claim:

The ornamental design for a glove, as shown and described.

CHARLES R. KOVAR.
